UNITED STATES PATENT OFFICE

**ARLINE A. GRATZ, OF MINNEAPOLIS, MINNESOTA, ASSIGNOR TO DOMINION ELECTRICAL
MANUFACTURING CO., OF MINNEAPOLIS, MINNESOTA, A CORPORATION OF MIN-
NESOTA**

DESIGN FOR AN ELECTRIC HOT PLATE

Application filed February 14, 1931. Serial No. 38,659. Term of patent 7 years.

To all whom it may concern:

Be it known that I, ARLINE A. GRATZ, a citizen of the United States, residing at Minneapolis, in the county of Hennepin and State of Minnesota, have invented a new, original, and ornamental Design for Electric Hot Plate, of which the following is a specification, reference being had to the accompanying drawings, forming part thereof, wherein—

Fig. 1 is a perspective view of a hot plate showing my new design;

Fig. 2 is a front elevation of the same, and Fig. 3 is an end elevation.

What is claimed is:

The ornamental design for an electric hot plate, substantially as shown.

ARLINE A. GRATZ
